UNITED STATES PATENT OFFICE.

ALBERT F. JAMMES, OF NEW YORK, N. Y.

DESIGN FOR A BOTTLE.

SPECIFICATION forming part of Design No. 35,027, dated September 3, 1901.

Application filed August 2, 1901. Serial No. 70,675. Term of patent 14 years.

To all whom it may concern:

Be it known that I, ALBERT F. JAMMES, a citizen of the United States, residing at No. 4 West Thirty-seventh street, in the city of 5 New York, borough of Manhattan, county and State of New York, have invented and produced a new and original Design for Bottles, of which the following is a specification, reference being had to the accompanying drawings, forming part thereof, and in 10 which—

Figure 1 is a side elevation of a bottle, showing my new design. Fig. 2 is a cross-sectional view taken on the line X X of Fig. 1. 15 Fig. 3 is a bottom end view of the bottle.

As shown in the drawings, the leading or material feature of my design consists of the article provided with the following parts, disposed and arranged as shown in Fig. 1: a 20 top rim A, being convex, as shown in Fig. 2, and in the form of a circle around the top of the bottle in a horizontal plane, and neck B in the form of a symmetrical perpendicular cylinder, the outer edges of the sides of which 25 are perpendicular and terminating at the bottom in a rim C, similar to the top rim A, the same being convex, as shown in Fig. 2, and in the form of a circle around the bottom of the neck in a horizontal plane, and fluting D, 30 below rim C, and connecting the neck with the body of the bottle, the said fluting D being concave, as shown in Fig. 2, and narrow at the top, where it joins rim C, and broader at the bottom, spreading down and out in a 35 complex concave curve toward the sides of the body of the bottle and terminating at the bottom in a rim E in form similar to a low crown, the points of which are formed by the meeting of the component parts of the convex fluting D, the sides of said rim E being 40 straight and nearly perpendicular, inclining slightly out from the top toward the bottom, the whole rim E lying around the bottle in a horizontal plane, and the body G in the form 45 of an irregular perpendicular cylinder, the

sides of which project slightly beyond rim E, where the top of the body joins the rim E, forming a narrow edge, as shown at F, the sides of which edge are straight and incline out from the top toward the bottom. Below 50 the edge F the sides of the body G are nearly perpendicular, but somewhat convexly curved and drawn together at the bottom, narrowing the cylinder of the body G at the bottom, and the base I, consisting of a solid circular 55 disk projecting slightly beyond the sides of the body G, where the top of the base joins the body, forming a narrow edge, as shown at H, the sides of which edge are straight and incline out from the top toward the bottom, 60 the edge H being slightly scalloped and forming a waving edge around the top of the base I. The sides of the base I below the edge H are straight and nearly perpendicular, inclining slightly out from the top toward the 65 bottom. The bottom edge of the base I follows the conformation of the scalloped edge H, the depressions in the waving curve being flattened to a horizontal line at their lowest edge and forming the feet K K K, which 70 extend somewhat below the bottom of the bottle, as shown in Fig. 2. The center of the base forms the bottom of the bottle, on which a series of ribs R and grooves or corrugations S is disposed or arranged in the shape of a 75 many-pointed star, as shown in Fig. 3.

The main body G of the bottle is left plain.

Having described my invention, what I claim as new, and desire to secure by Letters Patent, is—

The design for a bottle, as herein shown and described.

In testimony whereof I have signed my name to this specification in the presence of two subscribing witnesses.

ALBERT F. JAMMES.
